COIN SLIDE

Bernhard C. Grunig, Chicago, Ill., assignor to
 A. B. T. Manufacturing Corp, Chicago, Ill., a
 corporation of Illinois

Application June 7, 1937, Serial No 146,801

11 Claims. (Cl. 194—97)

This invention pertains to coin-freeed control mechanisms and has among its important objects the provision of improved fraud-preventing means cooperable with the type of coin slide or control that has a reciprocable operating slide member.

Another object is the provision of fraud-preventing dogs cooperable with a coin slide member to prevent the operation of the device by means of "captive" coins or coins having attached thereto an extremely thin metal or like ribbon by means of which the coin can be withdrawn for repeated use after the slide has been operated.

Still another object is the provision of a device of the class described in which a coin, after it has been moved by the slide member a predetermined distance, cannot be retracted because of the automatic positioning of stopping and latching dogs engageable with the coin and the slide member in a particular manner so as to prevent return movement.

Yet another object is the provision of cooperating fraud-preventing dogs one of which is operated by a coin to cam another into position to latch the slide member positively against return movement.

Still another object is the provision of a standard frame structure adapted to operate with slides having coin pockets or openings of different sizes for reception of coins of different denominations, together with auxiliary attachment means therefor and useful to the same end.

Other novel aspects and objects of construction and operation of the invention will develop as the following specification proceeds in view of the drawing, in which:

Fig. 1 is a top plan view of a coin slide member utilizing the invention;

Fig. 2 is a vertical section along lines 2—2 of Fig. 1;

Fig. 3 is a bottom plan view of the device of Figs. 1 and 2;

Fig. 4 is a vertical section corresponding to the view of Fig. 2 except that the slide member is advanced toward coin depositing position;

Fig. 5 is a skeletonized front perspective view of the slide member and the principal non-retracting dogs;

Fig. 6 is an enlarged rear perspective in skeleton outline showing the dog-camming arrangement; while

Fig. 7 is a sectionalized perspective fragment showing the mounting plate, drop-out hole, and auxiliary adapting bracket;

Fig. 8 is a fragmentary sectional detail view of

a portion of the structure of Fig. 4, at an enlarged scale, showing the relationship between a cam and the blocking dogs.

The present invention provides improvements over the non-retracting dog mechanism described in U. S. Patent 2,082,037 of which I am one of the patentees and in which some of the basic structural features of the slide frame and depositing or ejecting mechanism, shown herein, are set forth in detail, reference being had to said patent for a more detailed discussion of such basic features.

In general, a form of coin slide with which my present invention can be used advantageously, is shown in Fig. 1 herein, and includes a main frame or guide having a vertical mounting plate or wall 10 and a horizontal shelf or bed plate 11 which extends at right angles in both directions from the mounting wall 10. Provided along the opposite longitudinal edges of the main frame shelf or bed plate 11, are opposite guide grooves 12 in which is slidably fitted a coin slide member 13 for reciprocable movement therein.

In the slide member 13 are a spaced apart coin pocket and sight opening 14 and 14' respectively (Figs. 4 and 5), one near the front and one near the rear of the slide member. Joining these pockets 14 is a longitudinally extensive slot or channel 15 (Fig. 5) which extends rearwardly beyond the rear or inner opening 14' as at 15' in dotted lines in Fig. 1 for purposes later to appear. Similarly, the slot 15 (Fig. 1) has a short forward extension 15'' beyond the front pocket 14. Adjoining this forward slot extension 15'' is a short, depending, inwardly slanting, grooved lug 16.

The purpose of this slot extension 15'' and grooved part of the lug 16 is to receive certain fraud-preventing dogs 17 and 18, both of which function independently, so to speak, of the novel dog arrangement of the invention, but which are nevertheless described to avoid confusion. These latter dogs 17 and 18 are mounted above the slide member 13 on the top side of the bed plate 11.

Provided in the frame just behind or to the left of the mounting plate 10, below the nose of a dog 17 (Fig. 2), is a drop-out hole 9 for undersized coins. The slide in the present instance being designed to receive five-cent pieces, and a one-cent piece would, under ordinary circumstances, drop out through hole 9.

The inner portion of the shelf or bed plate 11 has a coin discharge opening or well 19, to the right of which (Fig. 2) is an adjoining shelf or ledge 20, formed integrally with the bed plate,

onto which a deposited coin tends to move by its own weight out of the front pocket 14 of slide member 13 when the latter is moved inwardly. By continued inward movement of the slide 13, a coin 21 on shelf member 20 will be pushed by the depending grooved lug 16 past certain non-retracting dogs, later to be described, for ultimate movement into the well 19.

Mounted for reciprocable sliding movement below the well 19 on shelf or bed plate 11 is an auxiliary or second ejecting slide 22 normally urged toward the right or front and the mounting plate or wall 10 by means of a spring 23 so as to position a coin pocket or aperture 24, formed in the auxiliary slide, below the bottom of well 19 to receive a coin from the latter. Below the ejecting slide coin pocket 24 when the latter is in its normal position there is a small pan 25 attached by screws 26 to the bottom of frame 11 and serving to hold the ejecting slide member in place and also to prevent a coin, such as 21' (Fig. 4), from falling out of the pocket or aperture 24 in the ejecting slide member, except when the latter is shifted fully to the left so as to carry the coin past the rear edge of the pan, thus permitting the coin to be ejected or cleared from the slide mechanism.

Shifting of the auxiliary or second ejecting slide member 22 is effected by means of an up-standing pin 27 (Figs. 2 and 4) which projects upward into the rearward extension 15' of the longitudinal slot 15 in the main slide member and is there engaged by a shoulder notch 28 cut into the slide member in the rear channel extension 15' (Figs. 4 and 5). When the slide member 13 moves inwardly to its full stroke position, and when the ejecting slide member 22 is thus moved, a coin 21' (Fig. 4) resting in the rearmost coin pocket 24 in the auxiliary slide member 22 and on the pan 25, will be pushed beyond the rear (left) edge of the latter to gravitate into a suitable receptacle.

Mechanism including a full stroke dog 29 engageable with edgewise teeth 29' in slide member 13 (Figs. 1 and 5), prevents retrograde movement of the slide member while a coin remains in the coin pocket 14 and permits retrograde movement only when the slide member 13 has been moved to position a coin below the opening 14'. It may be remarked that the purpose of the rear sight opening 14' in main slide 13 is to permit the viewing of a deposited coin through the sight opening 19' overlying the well 19 (Figs. 1 and 2).

However, there is a limited amount of retrograde or return movement of the slide member, made possible by inherent structural peculiarities or clearances of the moving parts of the mechanism, and this feature has an important bearing on the special fraud-preventing dogs provided in the present invention.

Mounted conveniently on the lower rear bed plate 11 is a trio of dogs 30, 31, 32. The first of these, or the latching dog 30, is pivotally mounted as at 33 near the right-hand edge of the slide member 13, as seen in Figs. 2 to 6, so that its nose portion 34 extends upwardly through a slot in the bottom of the bed plate 11 for bearing engagement with the bottom of slide member 13. The slide member is provided with an edgewise notch 35 (Figs. 5 and 6) into which the nose 34 of dog 30 will be moved under certain conditions when the slide is pushed into a predetermined position, corresponding to that seen in Fig. 4, where a coin 21 has been moved between the nose 36 of the

middle or coin-stopping dog 31 and a lug 46, to be described.

Stopping dog 31 and the outer or second stopping dog 32 (which acts to block attempted retraction of coins by shims, wires, etc., once the coin has passed these dogs) are mounted on a common stud or pin 37, and these dogs are provided with spring means 40, 41, respectively, operable to urge the noses 36 and 38 of the same toward the slide member 13. The middle dog 31, however, has a widened or oversize pivot or pin hole 39 (Figs. 2, 4, 6) which makes it possible for the dog to shift transversely, especially in a vertical direction, on its axial mounting without rocking movement of the nose 36 or tail 43, and thus, cooperably with its biasing spring 40, to shift radially or transversely to accommodate the dog for operation with coins of various thickness, so that the basic fraud-preventive mechanism will operate reliably whether the coin be a one-cent piece or a five-cent piece, since it is contemplated that the testing chute may, by simple change, be made to test either denomination of coin.

At this juncture, it may be explained that the outer one 32 of the two stopping dogs 31, 32, has its nose 38 disposed for movement upwardly in a direction into the front coin pocket 14 (when the latter passes toward the shelf 20 and well 19), the nose 38 being spaced in a direction across the pocket opening transversely of the slide member away from the middle or main stopping dog 31, so that both of the latter dogs may engage the rear or trailing peripheral edge portions of the coin as the latter is moved inwardly past said dogs, whereby to prevent fraudulent retraction of the coin, it being noted that the middle dog 31 is disposed slightly in advance (toward the left, Figs. 6 and 8) of the dog 32.

At the rearward edge (Figs. 4 and 5) of the coin pocket or hole 14 is a small depending pin 50 which will engage the forward or advancing edge of the coin 21 upon an attempted retraction of slide, before the latter has made its full inward stroke (as in the situation of Fig. 4, for instance), the pin urging the coin against the spaced noses 36 or 38 of the pair of stopping dogs 31 and 32 respectively, provided the coin has been advanced past these dogs, but not far enough to move into the well 19, or even under the latter circumstances, if the coin is captive, when an attempt is made to retract the same by means of a shim or wire along with the slide member.

In addition, there is a fixed depending lug 46 attached to the bed plate 11 or a part thereon to overlie the nose 36 of the middle dog. This lug is somewhat like the lug 46 in the aforementioned patent, and serves cooperably with the nose 36 of the middle dog 31, to pinch the coin and tilt it upwardly so that pin 50 may surely engage the leading edge of the coin upon attempted retraction as aforesaid after the coin has moved onto the nose 36 of the middle dog 31.

The latching dog 30 has a lateral ear or lug 42 (Figs. 4 and 6) which extends above the tail or end 43 of the middle stopping dog 31, and when the latter dog is pivoted by engagement with a coin, tail 43 will bear against lug 42 and pivot dog 30 and the nose 34 thereof will enter the edgewise notch 35 formed in slide member 13 at a point along its edge so that the nose 34 will, in synchronism with the inward movement of the slide member 13, engage the notch 35 therein as soon as the coin engages the nose 36 of stopping dog 31 and remains in the notch 35 during such en-

gagement. It is thereafter impossible to cause a withdrawal of the coin slide 13 which will be latched by the nose 34 because the dog 31 is immovable due to the presence of the coin between the nose 36 and lug 46 (Fig. 4), thus pivoting (or transversely shifting) the dog on pin 37 and causing the tail 43 thereof to bear against the lateral lug 42 of the latching dog 30. The harder the retractive pull, the more firmly does the latching dog 30 become wedged as a result of the 10 cam action of the stopping dog 31. This latter feature is of especial importance in those attempts at fraudulent operation wherein a thin metal ribbon is attached to an otherwise genuine coin and the latter deposited until the slide is operated, and thereafter withdrawn by the ribbon. Such an endeavor is utterly frustrated by the coaction of the middle stopping dog 31 and the latching dog 30, and even where coins or tokens of different thickness are used, legitimately or fraudulently, the provision of the enlarged pivot hole 39 assures the faithful operation of the dogs to this end.

Once the slide member is moved to complete inward position with the coin beneath the sight opening 14' the coin will have passed beyond engagement with the latching dog 30 and the stopping dog 31 to permit the latter two dogs to again assume normal position prior to withdrawal of the slide member 13.

Attention is called to the importance of the transverse or lateral shiftability of the middle stopping dog 31 in view of the fact that the nose 34 of the latching dog 30 must ride against the underside of the slide member except when it is raised into the notch 35, and thus there is sufficient yieldability on the part of the middle stopping dog 31, by virtue of its transverse shiftability and on the part of the latching dog 30 in so far as its operative association 42-43 with the middle stopping dog 31 is concerned, to permit adequate freedom of movement of both dogs without danger of interlocking, particularly when the coin is tilted in the pocket by action of stopping dogs 31 and 32 and the lug 46, in legitimate operation.

Because of the foregoing particular arrangement of the dogs, and especially the provision of means for shifting the stopping dog 31 transversely of its pivotal axis, the invention will insure against fraudulent operation of the kind specified, even though the coins used vary in thickness or diameter, and it adapts the basic operating mechanism to proper use with coins of several denominations, such as nickels or pennies. In the present embodiment, it is merely necessary to exchange the slide member 13 for one having a coin pocket 14 of suitable diameter.

It is important to observe that the drop-out hole 9 in the standard bed plate is usually of a maximum diameter slightly under the diameter of the largest coin to be used. Therefore, there is provided auxiliary adapting means for preventing smaller coins such as pennies from passing through the drop-out hole 9, such means being applied to those bed plates intended for use with smaller coins and thus obviating any necessity for duplication of dies and tools, so that the same bed plate may be used for at least three different arrangements: the largest size with a free drop-out, the large size with a restricted or partly blocked drop-out, and the smaller size with the partly blocked drop-out.

This auxiliary adapting means is in the form of an angle bracket 56 (Fig. 7) affixed by means

such as the rivets 51 to the rear vertical portion of the mounting plate 10, just below its juncture with the rear extension of the bed plate 11 and the drop-out hole 9 therein. The upper extension of this bracket is bifurcated to provide oppositely spaced horizontal arms 52, stamped into V-shape so that each arm has an outwardly diverged lip or flange 53, which underlies the bed plate 11 adjoining the edge of the hole 9 (Fig. 3); and also a vertical flange 54 dimensioned to extend into the drop-out hole 9 close to the peripheral edge thereof (Fig. 7) and thus provide opposite track-like insert portions over which a small diameter coin will glide as the slide member moves past the hole 9. The bracket also has cut-away portions at the right-hand juncture between the horizontal and vertical extensions, as viewed in Fig. 7, which permit free downward movement of the nose of a dog such as 18 (these vertical extensions not being shown but formed in the manner indicated at 55, Fig. 4).

Having thus specifically described my invention for purposes of illustration, it should be understood that it is my intention to include in the appended claims all equivalent means for realizing the same objects, as well as all modifications, rearrangements and combinations of the described structure coming fairly within the scope of my claims.

Having thus described my invention, what I claim as new and desire to protect by Letters Patent is:

1. In a coin-free control including a reciprocable coin slide member, fraud-preventive means comprising a latching member arranged for movement from a normal ineffective position to latch said slide member against return movement after the same has been advanced a predetermined amount in an opposite direction from an initial position, and dog means actuated by a coin moved by said slide member when the latter has been advanced a certain distance from said initial position for moving said latching member into latching position as aforesaid.

2. In a device of the class described including a coin slide member arranged for back and forth movement, fraud-preventive means comprising a main dog yieldingly urged into position for transient engagement by a coin moved by the coin slide member, means cooperable with said dog for tilting said coin when the same has been moved a particular distance in a particular direction from an initial position, and a latch dog arranged for actuation to be moved from a normally ineffective condition into latching engagement with said coin slide member to prevent return movement of the same oppositely to said particular direction when said coin slide member has been moved substantially said particular distance from the initial position, said main dog being arranged for movement by camming action therewith of said tilted coin to actuate and move said latch dog into effective latching position as aforesaid.

3. In a coin testing device, a reciprocable coin transporting slide member, and fraud-preventive means including a main dog arranged for pivotal movement toward and away from a coin transported by said slide member, said dog also being movable transversely of its pivotal axis toward and away from said transported coin, spring means normally urging said dog both pivotally and transversely into a normal position for engagement with a transported coin, said main dog being moved out of normal position when in en-

gagement with certain coin elements transported as aforesaid, a latch dog arranged for movement from a normally ineffective position into latching engagement with said slide member to prevent retractive movement thereof after the same has been advanced a predetermined amount in one direction from an initial position, and means providing operative connection between said main dog and latch dog for latching actuation of the latter by the main dog so long as the latter is out of normal position.

4. In a device of the class described, a reciprocable coin slide member having a coin pocket for holding a coin substantially in the plane of the slide member, a main dog pivoted for movement toward and away from a coin in said pocket, said dog also being shiftable in the same directions transversely of its pivotal axis, spring means normally shifting and pivoting said dog toward said slide member for transient engagement by a coin in said pocket, a latch dog arranged for movement by said main dog responsive to movement of the main dog out of normal position, into latching engagement with said slide member whereby to prevent retractive movement of the slide member from a predetermined advanced position away from an initial position, and means for tilting a coin substantially out of said pocket when the coin has been moved by the slide member to said predetermined position whereby to cam said main dog and operate the latch dog as aforesaid to prevent retraction of the slide member.

5. In a device of the class described, a reciprocable coin transporting slide member arranged to advance coins from one position to another when said slide member is moved in a particular direction from an initial position, a latch member arranged for movement from a normally ineffective position to latch said transporting slide member against retractive motion after the same has been advanced a certain distance in said particular direction, and means including a movable latch-operating member arranged to be engaged transiently and moved from a normal position by a coin advanced by said transporting slide member, to move the latching member into latching position.

6. A coin slide having a reciprocable coin-bearing slide member movable toward one of its reciprocal positions to transport a coin to a particular discharge point, and means for preventing the retraction of the slide member after said coin has been advanced a predetermined distance toward said discharge point, said means including a pivoted stop dog yieldingly disposed in the path of advance of said coin and arranged for cooperation with stationary coin-engaging means to block retractive movement of the coin after the same has advanced past said dog, stationary coin-engaging means cooperable with the stop dog as aforesaid, coin elements moving said dog out of a normal position in advancing past the dog, a latch dog arranged for movement into latching association with said slide member to prevent retractive movement of the same unless the slide member has been moved beyond a certain position and said coin has been discharged, said stop dog being arranged for operation when disposed out of normal position to engage and hold said latch dog against movement out of effective latching condition.

7. A coin slide having a reciprocable coin-bearing slide member movable toward one of its reciprocal positions to transport a coin to a par-

ticular discharge point, and means for preventing the retraction of the slide member after said coin has been advanced a predetermined distance toward said discharge point, said means including a pivoted stop dog yieldingly disposed in the path of advance of said coin and automatically operable to block retractive movement of the coin after the same has advanced past said dog, a latch dog operable from a normal ineffective condition to hold said slide member against retractive movement after the slide member has been moved a certain amount from an initial position but not enough to have carried said coin to said discharge point, said stop dog being arranged for operation to move and hold said latch dog in effective latching condition by engagement of a retracted coin bearing against said stop dog, and fixed coin guiding means substantially opposite said stop dog and against which the latter urges a coin, said stop dog also having freedom of transverse or radial movement relative to its pivotal axis, whereby the dog may shift on its pivotal mounting for operation by coins of varying thickness moving between the same and said coin guiding means, and means yieldingly urging said stop dog transversely toward said fixed coin guiding means.

8. The combination, with a coin slide member of the class described, of fraud preventive means including a pair of coating dogs one of which is arranged for movement out of a normally ineffective position to latch said slide member against movement when the slide member has been moved a certain distance from an initial position, and the other of which dogs is arranged for engagement and movement by a coin transported by said slide member to move the first-mentioned dog out of said normal position and for latching operation so long as there is a coin in engagement with said other dog.

9. In a device of the class described, means for preventing the fraudulent retraction of a coin slide member after the same has been moved a certain distance from an initial position, said means comprising a dog arranged for yielding engagement with a coin transported by said slide member, means for effecting movement of said coin against said dog to urge the latter out of a normal position as a result of transit of the coin relative to the dog, and a second dog arranged for movement from a normal ineffective position by said first-mentioned dog responsive to movement of the latter out of normal position as aforesaid so as to cause said second dog to lock said slide member against effective movement so long as the first-mentioned dog is disposed out of normal position by action of a coin as aforesaid.

10. In a device of the class described, fraud preventive means adapted for cooperation with a coin slide member, said means comprising a latch dog movable from a normal position to bear against said slide member, said slide member having locking means lockingly engaged by said dog when the slide member is in a certain position and the dog is moved out of normal position as aforesaid whereby the slide member will be locked against movement, a second dog mounted for both pivotal and shifting movement transversely of its pivotal axis toward said slide member, spring means pivoting and shifting said second dog into a normal position toward the slide member for engagement with a coin carried by the latter, means providing operative connection between said dogs and arranged so that movement of said second dog out of normal position

will effect movement of said first dog to bear against said slide member, in consequence of the yieldability of said first dog, for cooperation with said locking means, and means for moving a coin carried by said slide member into engagement with said second dog to urge the latter out of its normal position for locking operation of the first dog in the manner aforesaid when the slide member and coin carried thereby are in a predetermined position away from an initial position.

11. In a device of the class described, means for preventing fraudulent retraction of a coin slide member having a pocket in which a coin is carried, said means comprising a dog mounted for pivotal movement toward the slide member and pocket and also for shifting movement relative to its pivotal axis toward and away from said slide member, means yieldingly pivoting and shifting said dog into a normal position for engagement with a coin which is carried to or past

5 the dog in said pocket, means for moving said coin out of a normal position in said pocket to expose an edge portion of the coin when the latter has been moved to a certain position by the slide member, said dog engaging said edge portion to block the same and prevent retractive movement of the slide member when such movement is attempted after the coin has been moved past said dog, said coin also being effective when engaged with said dog before passing the latter and while the coin is out of normal position in the pocket, to pivot said dog out of its normal position, and a latch dog moved by said first-mentioned dog from a normally ineffective position into latching engagement with said slide member to lock the latter against motion so long as the first-mentioned dog is disposed out of its normal position by the coin in the manner aforesaid.

BERNHARD C. GRUNIG.
